UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.
SEWING-MACHINE-NEEDLE-SETTING MEANS.

1,072,472.

Specification of Letters Patent.

Patented Sept. 9, 1913.

Application filed October 26, 1912. Serial No. 727,897.

To all whom it may concern:

Be it known that I, JOHN KIEWICZ, citizen of the United States, residing at Hyde Park, in the county of Norfolk and State 5 of Massachusetts, have invented certain new and useful Improvements in Sewing-Machine-Needle-Setting Means, of which the following is a specification, reference being had therein to the accompanying drawing.

10 My invention relates to sewing machine needle setting means, and broadly speaking the improvement thereof is adapted to various classes and descriptions of sewing machines.

15 The principal object hereof is to provide for the ready setting of the needle in proper relative position by a needle setting means originally adjusted or standardized, so that in subsequent insertion of new needles by 20 operators the same will invariably be brought to the proper predetermined position.

Another object hereof is to adapt such a 25 needle-setting means or device to that type of sewing machine wherein an oscillating needle bar carries an offset needle, or in which the needle bar has an offset or enlarged head or end upon which the needle is secured or clamped with its butt end projecting rearward therefrom. Sometimes in 30 a sewing machine of this type the enlarged or offset head of the needle bar is so shaped as to adapt it to overhang the bearing in which the needle bar slides to and fro, and 35 the presence of the bearing in this location would stand in the way of any heretofore known needle setting or stopping device.

It is an object hereof to provide a needle 40 setting or stopping device which is capable of being employed in the types of sewing machine referred to, illustrations of which are seen, for example, in prior patents of Reece No. 404,863, patented June 11, 1889, and Dahl & Hagelstein No. 987,966, 45 patented March 28, 1911.

In the accomplishment of the above objects the present invention consists in the novel structures, combinations, arrangements, parts and other features hereinafter 50 described or illustrated.

I will first describe one form of device embodying the present invention and will thereafter point out the novel features in the claims.

In the accompanying drawings forming a 55 part hereof, Figure 1 is a left side elevation of one form of embodiment of the present invention in which for convenience the same is applied to the type of machine having a horizontal needle bar and needle, such as is 60 referred to in the prior patents above named, suitable for blind stitching or for finishing button-holes. Fig. 2 is a right side elevation of the forward end of the needle bar and the needle carrying device thereon. 65 Fig. 3 is a top view of the parts shown in Fig. 2. Fig. 4 in perspective shows all of the needle securing and setting parts detached from each other, but in substantially 70 their proper relative position for assembling. Fig. 4^a shows a detailed end view of the needle stop.

Similar numerals or letters of reference 75 designate corresponding parts in the several figures of the drawings.

A needle bar or carrier 5 is shown, this being of the type having an offset needle or having an offset or enlarged forward end or head, 6, to which the offset needle 7 is secured by the needle clamp piece 8, or other 80 convenient securing device. As will be seen herein and in said prior patents, the needle is held in the securing device 8, so that the needle's butt will project rearward of the offset needle bar head. Such an arrangement of needle bar and needle may be employed in combination with a horizontal work support 9, which has a recess for the depression of the work therein, and which also has a needle passage as in said prior 85 patents, a presser-foot 10, and a bender 11 for bending the work into the recess for the purposes of blind stitching or button-hole finishing. A needle bar of this type should be firmly mounted, and the same is shown 90 as having a rear bearing 12 and a front bearing 13, these being in the form of upright standards from the frame of the machine, as in said prior patents. Any suitable connection, such as link 14, may be employed for oscillating the needle bar. It 100 will be seen that the enlarged head of the needle bar is not only offset, but is so shaped as to overhang the forward bearing 13 to a slight extent, and the specific form of needle 105 setting device herein is also preferably arranged to overhang the bearing.

One convenient means of securing the

needle in place is through the clamp piece 8 already referred to, which may be arranged to press directly against the needle while the latter lies in an open groove, seen more particularly at 15 in Fig. 4, formed in the head 6. Below the groove 15 is seen a bearing ledge 16, the purpose of this being that the clamp piece 8 of symmetrical form may bear with even pressure at both its upper and lower sides, namely, against the needle and against the ledge 16. The clamp piece has a screw shank 17, projecting through the head 6, and it is tightened in place by a clamp nut 18, beneath which may be placed a washer 19. On locating the needle in the open groove 15 and tightening the nut 18, the clamp piece will firmly bear on the needle and hold it, at the same time permitting the quick detachment of the parts for removing the needle.

According hereto, a needle stop 20 is provided which constitutes a stop piece for the shank or butt end of the needle, and the same is adjustable, as hereinafter described. Some part of this needle stop 20 is arranged to project laterally with respect to the needle, so as to be contacted by the needle's butt for determining the needle's position. Preferably this is accomplished by arranging the body of the needle stop in a longitudinal direction and providing a laterally projecting flange 21 at the rear end, shown for convenience as of triangular shape.

The needle stop 20 is to be secured to the head 6 so as to project rearwardly therefrom, and as a matter of great convenience and simplification I have provided the stop 20 with an elongated slot 22, capable of engaging about the screw shank 17 of clamp piece 8, so as to be secured therewith when the clamp nut 18 is tightened. The outer or rearward end of the needle stop 20 is also properly held or positioned, this being accomplished herein by means of a screw 23, adapted to engage in a threaded longitudinal hole 24 in the head 6. The clamp piece 8, and the screw 23 coöperate to hold the needle stop in a definite position. At the same time the position of the needle stop is adjustable by the adjustment of the screw 23 inward and outward. The screw 23 and the stop 20 are shown connected to each other by a mutually engaging slot 25 in the triangular flange 21 of the needle stop and the annular groove 26 near the head of the screw 23. By this arrangement, upon loosening the clamp nut 18 the screw 23 may be turned for adjusting the position of the needle stop flange 21. When the parts are properly adjusted and the needle is secured in place, the clamp nut 18 holds the parts against accidental displacement. At the same time, the needle is easily detachable and replaceable by loosening the clamp nut, and, as explained, the needle stop is origi-

nally adjusted or standardized in a simple manner to such position that each needle upon insertion will bear its proper and accurate relation to the other parts of the machine. When the screw 23 has once been engaged in the recess 25 of the flange 21, said flange may be slightly distorted so as to somewhat close the recess about the screw, thereby rendering permanent the connection between the two and preventing accidental displacement, in a manner, for example, as indicated in Fig. 4^a.

It is obvious that many matters of arrangement, combination and mere detail may be indefinitely varied and it is therefore desired not to restrict the present application thereto, except as may be specified in the appended claims.

By the above-described devices, combinations and arrangement, it will be seen that the objects and advantages before recited are attained, and other advantages will be perceived by those acquainted with the art to which the invention relates.

What I claim and desire to secure by Letters Patent is:

1. A sewing machine needle setting means comprising, in combination with a needle carrier of the type having an offset or enlarged head or end, a needle securing device on said head adapted to hold a needle with its butt projecting rearward therefrom and a longitudinally adjustable needle stop comprising a plate carried by said head extending rearward of said head and there flanged, and an adjusting screw for varying the stop's position, said screw having a groove engaging an aperture in said flange.

2. A sewing machine needle setting means comprising, in combination with a needle carrier of the type having an offset or enlarged head or end a needle securing screw-clamp on said head having a clamp screw, and adapted to hold a needle with its butt projecting rearward therefrom and a longitudinally adjustable needle stop comprising an apertured plate carried by said head extending rearward of said head and there flanged, and an adjusting screw for varying the stop's position; the aperture of said stop plate engaging the clamp screw of said needle securing means whereby to assist the positioning of said stop.

3. A sewing machine needle setting means comprising in combination with a needle carrier of the type having an offset head, a needle securing device on said head adapted to secure a needle with point and butt ends both longitudinally projecting, exteriorly therefrom, and a longitudinally adjustable exterior needle stop having a stop part laterally projecting into the needle line adapted to be contacted by the needle butt for determining the needle's position.

4. A sewing machine needle setting means

comprising in combination with a needle carrier of the type having an offset head, a needle securing device on said head adapted to secure a needle with point and butt ends both longitudinally projecting exteriorly therefrom, and a longitudinally arranged exterior needle stop detachably mounted on said head having a body and a stop part laterally projecting from said body into the needle line adapted to be contacted by the needle butt for determining the needle's position.

5. A sewing machine needle setting means comprising in combination with a needle carrier of the type having an offset head, a needle securing device on said head adapted to secure a needle with point and butt ends both longitudinally projecting exteriorly therefrom, and a longitudinally adjustable exterior needle stop having a plate portion secured upon said head and a stop flange laterally projecting from said plate portion into the needle line to be contacted by the needle butt for determining the needle's position, and means for securing the plate portion of said stop upon the said head in its adjusted position.

6. A sewing machine needle setting means comprising in combination with a needle carrier of the type having an offset head, a needle securing device on said head adapted to secure a needle with point and butt ends both longitudinally projecting exteriorly therefrom, a longitudinally adjustable exterior needle stop having a plate portion secured upon said head and a stop flange laterally projecting from said plate portion into the needle line to be contacted by the needle butt for determining the needle's position, and an adjusting screw for varying the stop's position and securing the stop body to said head.

7. In a sewing machine, the combination of an oscillating needle carrier, a bearing therefor, said carrier having an offset head adapted to overhang said bearing when in retracted position, needle securing means for holding a needle in offset position on said head with its two ends both projecting exteriorly longitudinally from said head, and an exterior needle stop carried by said head and adapted to have the needle butt contact it.

8. In a sewing machine, the combination of an oscillating needle carrier, a bearing therefor, said carrier having an offset head adapted to overhang said bearing when in retracted position, needle securing means for holding a needle in offset position on said head with its two ends both projecting exteriorly longitudinally from said head, and an exterior needle stop carried by said head and adapted to overhang said bear-

ing, said stop having a device for adjusting it longitudinally and a device for securing it where adjusted.

9. In a sewing machine, the combination of an oscillating needle carrier, a bearing therefor, said carrier having an offset head adapted to overhang said bearing when in retracted position, needle securing means for holding a needle in offset position on said head with its two ends both projecting exteriorly longitudinally from said head, and an exterior needle stop carried by said head and adapted to overhang said bearing, said stop consisting of an elongated member extending alongside the needle and projecting to an adjustable extent longitudinally of said head and having a lateral flange adapted to have the needle butt contact it.

10. A sewing machine needle setting device comprising in combination with the needle carrier or bar, a needle stop adjustable longitudinally of the needle and carrier, an exteriorly accessible locking device operative after adjustment of such stop for locking the stop in adjusted position, and a needle securing device for detachably securing a needle in the position determined by said stop's adjustment; both the needle's butt and the stop's contacting portion being located to the rear of the needle body and said locking device respectively, and mutually contacting each other at a point exterior to the needle carrier.

11. A sewing machine needle setting device comprising in combination with the needle carrier or bar, a needle stop adjustable longitudinally of the needle and carrier, and freely slidably longitudinally relatively thereto while in engagement with the carrier, an exteriorly accessible locking device operative after adjustment of such stop for locking the stop in adjusted position, and a needle securing device for detachably securing a needle in the position determined by said stop's adjustment, with the needle butt in contact with said stop; both the needle's butt and the stop's contacting portion being located to the rear of the needle body and said locking device respectively.

12. A sewing machine needle setting device comprising in combination with the needle carrier, a needle stop having a longitudinal slot and adjustable by reason of said slot longitudinally of the needle and carrier, an exteriorly accessible locking device operative after adjustment of such stop for locking the stop in adjusted position, and a needle securing device for detachably securing a needle in the position determined by said stop's adjustment; both the needle's butt and the stop's contacting portion being located to the rear of the needle body and said locking device respectively, and mutually contacting each other at a point exterior to the needle carrier.

13. A sewing machine needle setting device comprising in combination with the needle carrier, a needle stop having a longitudinal slot and adjustable by reason of said slot longitudinally of the needle and carrier, an exteriorly accessible screw-threaded locking device engaged in said slot, operative after adjustment of said stop for locking the stop in adjusted position, and a needle securing device for detachably securing a needle in the position determined by said stop's adjustment; both the needle's butt and the stop's contacting portion being located to the rear of the needle body and said locking device respectively.

14. A sewing machine needle setting device comprising in combination with the needle carrier, a needle stop adjustable longitudinally of the needle and carrier, and

located exteriorly to the carrier, a locking device operative after the stop's adjustment for locking the stop to the exterior of the carrier in adjusted position, and a needle securing device for detachably securing a needle in the position determined by said stop's adjustment; both the needle's butt and the stop's contacting portion being located to the rear of the needle body and said locking device respectively, and mutually contacting each other at a point exterior to the needle carrier.

In testimony whereof I affix my signature in presence of two witnesses.

JOHN KIEWICZ.
